(57) **CLAIM**

The ornamental design for a trash can, as shown and described.

DESCRIPTION

FIG. 1 is a front, left, and top perspective view of a trash can, showing my new design;

FIG. 2 is a rear, right, and bottom elevation view thereof;
FIG. 3 is a front elevation view thereof;

FIG. 4 is a rear view thereof;

FIG. 5 is a top plan view thereof;

FIG. 6 is a bottom plan view thereof;

FIG. 7 is a left side elevation view thereof;

FIG. 8 is a right side elevation view thereof;

FIG. 9 is an enlarged view of an encircled area labeled "9" in FIG. 1;

FIG. 10 is a front, right, and top perspective view of the trash can of FIG. 1 in a use state;

FIG. 11 is a front, left, and top perspective view of a second embodiment of a trash can, showing my new design;

FIG. 12 is a rear, right, and bottom perspective view thereof;
FIG. 13 is a front elevation view thereof;

FIG. 14 is a rear view thereof;

FIG. 15 is a top plan view thereof;

FIG. 16 is a bottom plan view thereof;

FIG. 17 is a left side elevation view thereof;

FIG. 18 is a right side elevation view thereof;

FIG. 19 is an enlarged view of an encircled area labeled "19" in FIG. 11; and,

FIG. 20 is a front, right, and top perspective view of the trash can of FIG. 11 in a use state.

The evenly-dashed broken lines depict portions of the trash can that form no part of the claimed design. The dot-dash broken lines shown in FIGS. 1, 9, 11, and 19 framing portions of the trash can for enlargement purposes form no part of the claimed design.

1 Claim, 20 Drawing Sheets
